[57] ABSTRACT

The invention relates to the removal of rocks or stones from workings, for example a quarry or an open-cast mine. It concerns more particularly an installation for the evacuation of rocks or stones from a workings to a continuous transporter or conveyor. This installation comprises a chassis movable over the ground of the workings, a carriage movable on a rolling path along the continuous transporter or conveyor, a jib connecting the chassis to the carriage and consisting of a first arm carrying a continuous conveyor and a second arm carrying another continuous conveyor, both arms being articulated to one another on a substantially vertical pivot suspended from a structure which is supported by the chassis or by the carriage. The first arm of the jib is articulated to the chassis on a substantially vertical pivot, and the second arm is articulated to the carriage round another vertical pivot which comprises a trunnion rotatably mounted in a bearing round a substantially vertical axis, the trunnion being articulated to the end of the second arm round an axis which is substantially horizontal and substantially transverse to the conveyor of the second arm, and the bearing being articulated to the carriage round an axis which is substantially horizontal and substantially transverse to the continuous transporter or conveyor, said horizontal axes being situated substantially in the same plane.

**INSTALLATION FOR THE EVACUATION OF
ROCKS FROM A WORKING TO A CONTINUOUS
TRANSPORTER**

DESCRIPTION OF THE INVENTION

The invention relates to the removal of rocks or stones from workings, for example a quarry or an open-cast mine. It concerns for example the removal of barren rocks or minerals covering a deposit and taking them to a treatment unit situated away from the deposit.

The transfer of rocks from an exploitation zone of workings to a treatment unit is usually effected by lorries or by means of other automotive vehicles. A disadvantage of this type of transport lies in the fact that it is essentially discontinuous. It necessitates moreover considerable investment in material and a substantial number of personnel, not only for driving these vehicles but also for their maintenance. This method of transport has the additional disadvantage of the difficulty in negotiating hilly ground and it involves the necessity of laying out tracks for carrying these vehicles. In particular, in the case of deep workings in a quarry or open-cast mine, it is necessary to provide terraced access roads between the workings and the utilisation zone, in this instance a treatment unit.

It is known that to effect a rapid and simple removal of rocks from workings, it is advantageous to use continuous conveyors, for example conveyor belts. These continuous conveyors are in fact of simple and automatic operation and only require a limited number of personnel. They enable rapid conveyance of rocks over long distances, for example up to a treatment unit situated away from the workings.

The arrangement of continuous conveyors of this type necessitates an expensive substructure and suitable preparation of the ground, so that it is of prime importance to establish them away from an exploitable deposit, or failing this, in a zone of the deposit where exploitation is only foreseen in the distant future.

To transfer of extracted rocks from the zone of exploitation of the deposit to the continuous conveyor requires therefore an intermediate handling means.

It is known for this purpose to make use of an installation which moves over the floor of the workings in the immediate vicinity of the exploitation zone and comprising a chassis which can move over the floor of the workings, a jib fixed to the chassis and extending over the continuous conveyor, a conveying device on the jib and a means for feeding the conveying device with rocks. The conveying device provided on the jib can be for example a continuous conveyor of the belt type or pallet type. The means for feeding the conveying device with rocks to be removed can be a hopper, fed by an excavator shovel or other extraction device. The chassis is generally mounted on caterpillars in order to facilitate its movement over the floor of the workings and so that it can follow therefore the working face. If necessary it could be mounted on series of tyred wheels.

With an installation of this type it is sufficient to suitably guide the jib in order that its end is situated above the continuous conveyor: thus the rocks removed by the conveying device provided on the jib are poured by gravity on to this continuous conveyor.

This known installation has unfortunately, the disadvantage of only permitting the removal of rock over a

limited distance, in view of the fact that the length of overhang is limited by considerations of rigidity of the structure and balancing of the installation. The greater the difference in levels between the exploitation zone of the workings and the continuous conveyor, the greater is the reduction in this distance, so that this known installation can only be used with difficulty in the case of deep quarries or mines.

Another disadvantage of this known installation lies in the necessity of constantly maintaining the end of the jib above the continuous conveyor during the movement of the chassis over the floor of the workings, which is particularly difficult and necessitates competent personnel.

According to the invention there is provided an installation for the evacuation of rocks or stones from a workings to a continuous transporter or conveyor, comprising a chassis movable over the ground of the workings, a carriage movable on a rolling path along the continuous transporter or conveyor, a jib connecting the chassis to the carriage and consisting of a first arm and a second arm articulated to one another on a substantially vertical pivot, the first arm being articulated to the chassis on a substantially vertical pivot and the second arm being articulated to the carriage round another substantially vertical pivot, the first arm carrying a first continuous conveyor which discharges onto a second continuous conveyor carried by the second arm of the jib, the second conveyor discharging onto the continuous transporter or conveyor, in which the common articulation pivot of the two arms of the jib is suspended from a structure which is supported by the chassis or by the carriage and in which the pivot of articulation of the second arm on the carriage comprises a trunnion rotatably mounted in a bearing round a substantially vertical axis, the trunnion or the bearing being articulated to the end of the second arm round an axis which is substantially horizontal and substantially transverse to the conveyor of the second arm, and the bearing of the trunnion being articulated to the carriage round an axis which is substantially horizontal and substantially transverse to the continuous transporter or conveyor, said horizontal axes being situated substantially in the same plane.

In the installation according to the invention the jib, constituted by two successive articulated arms, rests at one end on the chassis which can move over the floor of the workings and at the other end on the carriage arranged in the vicinity of the continuous conveyor. There is thus eliminated the overhang of the jib so that the latter can be very long without prejudicing the equilibrium of the installation nor its stability.

Furthermore, in view of the fact that the jib is formed by two arms articulated to one another and also to the chassis and to the carriage and that the latter is fixed to a roller track along the continuous conveyor, it will be understood that during the movement of the chassis over the floor of the workings, the end of the jib is constantly maintained above the continuous conveyor. During the movement of the chassis over the floor of the working and/or during the movement of the carriage along its roller track, the two arms of the jib behave in the manner of the two arms of a pair of drawing compasses, so that the chassis can easily approach the continuous conveyor or on the contrary move away therefrom up to a distance equal, at maximum, to the complete spreading of the two arms of the jib: this dis-

tance can be very large for the reasons explained previously.

In order to prevent the carriage from leaving the roller track under the action of a transverse force following complete spreading of the arm of the jib, it can be advantageous to provide on the two arms a warning device indicating to the operator when the angle between the two arms is near to 180°.

In a special form of embodiment of the installation in accordance with the invention, the articulation pivot common to the two arms of the jib comprises a trunnion mounted rotationally in a bearing about a substantially vertical axis; this trunnion is articulated at the end of one of the arms about a substantially horizontal axis substantially transverse to the conveying device of the arm, and the bearing is articulated at the end of the other arm about a substantially horizontal axis substantially transverse to the conveying device of the other arm, the two horizontal axes being situated substantially in the same plane.

As a variant the articulation pivot of the first arm on the chassis can comprise a trunnion mounted rotationally in a bearing about a substantially vertical axis, the bearing being mounted on a frame which can swivel on the chassis and the trunnion being fixed to a support articulated at the end of the first arm about a substantially horizontal axis substantially transverse to the conveying device of the arm. The respective positions of the trunnion and of the bearing can be reversed.

This variant of the installation according to the invention is specially adapted to the case of uneven workings. In fact it makes it possible to maintain in horizontal position the transverse axes of the respective conveying devices of the two arms of the jib, whatever the inclination of the ground over which the chassis moves. For this purpose it is sufficient to swivel the frame appropriately at any time on the chassis so as to keep constantly vertical the axis of rotation of the articulation pivot of the first arm on the chassis. In order to facilitate the appropriate swivelling of the frame on the chassis, advantageously there can be provided an automatic stabilising device connecting the frame to the chassis.

In view of the great length which the jib might have, this form of embodiment of the installation according to the invention can easily be used in the case of a deep quarry or mine in which the difference in levels between the continuous conveyor and zone of exploitation is considerable.

In the machine according to the invention, it can be advantageous to provide a device making it possible to lock the horizontal axis of rotation of the pivot on the carriage, when the latter is stopped, so as to fix the axis of rotation of the pivot vertically and to thus prevent twisting of the jib, for example through oscillation of the latter under the action of a side wind.

With a view to increasing the possibilities of the installation according to the invention, it can comprise in a modified form of embodiment, a second jib connecting the chassis or the carriage to a vehicle movable over the ground of the workings, the second jib comprising a first arm which is articulated to the chassis or to the carriage on a substantially vertical pivot and a second arm which is articulated to the vehicle on a substantially vertical pivot, the two arms being further articulated to one another on a substantially vertical common pivot which is suspended from a structure supported by

the vehicle or the chassis or carriage, the two arms of the second jib respectively carrying two continuous conveyors which discharge from one to the other and connect the vehicle to the chassis or to the carriage.

5 In this modified form of embodiment of the installation according to the invention, the vehicle can be made in a similar manner to the chassis. It can for example be mounted on caterpillars or on tyres, according to the type of ground over which it is intended to manoeuvre.

The utilisation of a second jib makes it possible to considerably increase the reach of the installation according to the invention between the zone of extraction and the continuous conveyor, when the second jib connects the vehicle to the chassis.

In the case in which the second jib connects the vehicle to the carriage, the installation according to the invention makes it possible to feed the continuous conveyor starting from two separate extraction zones of 20 the workings, and consequently to increase considerably the rate of flow of extracted and removed rocks.

25 In this modified form of embodiment of the installation according to the invention, the connection of the second jib to the vehicle and, if necessary, to the chassis can be effected in a similar manner to the connection of the first jib to the chassis.

When the second jib joins the vehicle to the carriage of the installation, its articulation pivot to this carriage can advantageously be similar to the articulation pivot, in accordance with the invention, of the first jib on the carriage.

30 It can likewise be advantageous if the articulation pivot common to the two arms of the second jib comprises in accordance with the invention, a trunnion rotatably mounted in a bearing round a substantially vertical axis, the trunnion being articulated to the end of one of the arms, round an axis which is substantially horizontal and substantially transverse to the conveyor of the arm and the bearing being articulated to the end of the other arm, round an axis which is substantially horizontal and substantially transverse to the conveyor of the other arm, the two horizontal axes being situated substantially in the same plane.

35 Specific embodiments of the invention will now be described by way of example with reference to the accompanying drawings, in which :

40 FIGS. 1a and 1b show in elevation a first form of embodiment of the installation according to the invention, in which the two arms of the jib are arranged in alignment with one another, the two Figures joining with one another at the line A—A,

45 FIG. 2 is a plan view of the installation represented in FIGS. 1a and 1b, in which the two arms of the jibs are bent,

50 FIGS. 3 and 4 show on a larger scale two details of FIG. 2,

55 FIG. 5 is, on a larger scale, an outline view of the installation represented in FIGS. 1 and 2, viewed in the direction of the arrow V in FIG. 1,

60 FIG. 6 shows diagrammatically, on a larger scale, a detail of FIG. 1a,

65 FIG. 7 is, on a larger scale, a side view in the direction of the arrow VII of FIG. 1b, of the articulation of the jib on the carriage,

70 FIG. 8 is a side view, partly broken away, of a feeder-crusher in accordance with the invention, provided in the installation according to the invention,

FIG. 9 is a longitudinal view in elevation, partly broken away, of the feeder-crusher in FIG. 8,

FIG. 10 is a longitudinal view in elevation of a special form of embodiment of the chassis of the installation in FIGS. 1 and 2,

FIGS. 11a and 11b show in plan a modified form of embodiment of the installation according to the invention, the two Figures joining up at the line B—B,

FIG. 12 is a longitudinal view in elevation of the chassis in FIGS. 11a and 11b,

FIG. 13 shows in longitudinal elevation a variant of the chassis of the installation in FIGS. 11a and 11b, and

FIG. 14 shows in plan another special form of embodiment of the installation according to the invention.

In the Figures the same reference numbers indicate identical elements.

In a first form of embodiment represented in FIGS. 1 to 9, the installation according to the invention comprises a chassis designated by reference numeral 1. The chassis 1 is mounted on caterpillar tracks 2 ensuring its movement over the floor of the workings, for example a quarry or open-cast mine. In accordance with the invention a frame 4 is fixed to the upper part of the chassis 1 by means of universal joints 5 which allow swinging movements of the frame 4 on the chassis 1, both parallel and transverse to an axial plane of the chassis 1. Jacks 57 are arranged between the chassis 1 and the frame 4 to ensure the desired orientation of the frame 4 on the chassis 1. A platform 7 is articulated on the frame 4 about a pivot 6, substantially perpendicular to the frame 4. The pivot 6 is formed by a trunnion fixed to the platform 7 and mounted rotationally in a bearing fixed onto the frame 4. The trunnion and the bearing can constitute for example two cages of a ball or roller bearing.

The jacks 57 are controlled by a stabilizing device, for example a set of gyroscopes ensuring that the axis of rotation of the pivot 6 remains vertical during the movement of the chassis 1 over the floor 3 of the workings in the vicinity of the extraction zone. The platform 7 bears at one of its ends a jib 8. The jib 8 is formed by two articulated arms 9 and 10 each constituted by a metal lattice structure. The arm 9 is articulated to the platform 7 on pivots 11 about an axis transverse to the arm 9 and perpendicular to the axis of rotation of the pivot 6. The arm 9 is supported by a cable 12 which is wound round a winch 13 mounted on the platform 7 and which is connected to the arm 9 by means of a pulley system. The pulley system is formed by a pulley shell 14 attached to the arm 9 and of a pulley shell 15 attached to the upper end of an upright 16 articulated to the platform 7. The arm 10 is joined to the end of the arm 9 by an articulation 17. The latter is represented in a detailed manner in FIG. 3. It is formed by a trunnion 18 mounted rotationally in a bearing 20. In accordance with the invention the trunnion 18 is articulated at the ends of two uprights 66 of the arm 9, by means of two pivots 19 about an axis substantially transverse to the arm 9. In a similar way the bearing 20 is articulated at the ends of two uprights 67 of the arm 10, by means of two pivots 21 about an axis substantially transverse to the arm 10. Furthermore the trunnion 18 is mounted rotationally in the bearing 20 about an axis which is substantially perpendicular to the axis of the pivots 19 and to the axis of the pivots 21. The axis of the pivots 19 and the axis of the pivots 21 are substantially in the same horizontal plane.

In the articulation 17 the trunnion 18 and the bearing 20 can be two cages of a ball or roller bearing.

The other end of the arm 10 is maintained above a continuous conveyor 22 which is intended to be fed by the installation with rocks extracted in the exploitation zone of the workings in the vicinity of the chassis 1. The continuous conveyor 22 is for example constituted by a conveyor belt or by a pallet-type continuous conveyor. For this purpose a gantry 23 straddles the continuous conveyor 22 and is mounted on a roller track constituted by two rails 24 arranged on either side of this conveyor and parallel thereto. The gantry 23 supports on its upper part the end of the arm 10 by means of an articulation 25, similar to the articulation 17 and represented in detail in FIG. 4. It comprises in accordance with the invention a trunnion 26 which is articulated to two uprights 30 of the arm 10, on two pivots 27, about an axis substantially transverse to the arm. The trunnion 26 is furthermore mounted rotationally in a bearing 28 about an axis substantially perpendicular to the axis of the pivots 27. The bearing 28 is itself articulated to the gantry 23, on two pivots, about an axis substantially transverse to the continuous conveyor 22 and to the rails 24 and substantially perpendicular to the axis of rotation of the trunnion 26 in the bearing 28. The axis of the pivots 27 and the axis of the pivots 29 are situated substantially in the same horizontal plane.

In the articulation 25, the trunnion 26 and the bearing 28 can likewise be two cages of a ball or roller bearing.

A counterweight 33 is provided to balance the weight of the arm 10 about the pivots 27. The counterweight 33, whose centre of gravity is situated below the pivots 27 and 29, assists moreover in maintaining the axis of rotation of the trunnion 26 vertically in the bearing 28, effected by the jacks 57.

It can be advantageous to provide a device for damping vertical oscillations of the jib 8, caused by the movement of the chassis 1 over bumpy ground or by the discharge of rocks into a hopper 35 (described later) arranged on the platform 7 of the chassis 1.

In the installation of FIGS. 1a and 1b the damping device 105 is interposed between the arm 9 and the pulley shell 14. The damping device 105 represented diagrammatically in FIG. 6, comprises a spring 106 compressed between a plate 107 connected to the shell 14 and a plate 108 connected to the arm 9. The connection of the plate 108 to the arm 9 comprises a shock absorber 109. The shock absorber 109 is of the single acting type and is provided to brake any movement of the two plates 107 and 108 corresponding to a separation of the two plates from one another. Thus if the platform 7 swings in the direction of the arrow X (FIG. 1a) under the action for instance of the dropping of a very large lump of rock into the hopper 35, the swinging is absorbed at least partly by the spring 106, which reduces the amplitude of the swing of the jib 8. The subsequent expansion of the spring 106 is damped by the shock absorber 109.

As a variant the damping device 105 can be interposed between the end of the cable 12 and its fastening point 110 to the upright 16. The damping device 105 could likewise serve as a connection between the winch 13 and the platform 7.

According to another variant the hopper 35 could be provided at its end with a kinetic energy damping support which could for example be constituted by one or

several feet provided with a hydraulic damping device, the feet being retractable and able to be applied against the ground during the loading of the hopper. This system could advantageously be replaced by a resilient mounting of the hopper 35 in relation to the chassis 1, the damping device absorbing the kinetic energy at the time of impact when the hopper is charged rapidly and discontinuously.

It is advantageous to provide in addition a locking device making it possible to prevent the relative rotation of the bearing 28 and of the gantry 23 about the pivots 29 when the gantry is stationary, so as to maintain the axis rotation of the trunnion 26 vertically in the bearing 28. There is thus prevented twisting of the jib 8 through swinging of the latter, under the action for example of a side wind.

There is represented in FIG. 7 a special form of embodiment of this locking device. According to the invention this device comprises two jacks 68 which are arranged between the bearing 28 and the cross-members of the gantry 23, on either side of the axis of rotation of the pivots 29. The piston rods 71 of the jacks 68 are articulated to the bearing 28 and their cylinders to the cross-members 72, respectively on pivots 73 and 74 substantially parallel to the pivots 29. The chambers of these jacks 68 are moreover in communication with one another through a pipe 75 provided with an obturation valve 76.

During the movement of the chassis 1 over the workings 3 and/or of the gantry 23 over its rails 24, the valve 72 is open. Therefore the oil in the jacks 68 can circulate freely between the chambers of the jacks 68 so as to permit a free rotation of the bearing 28 on the gantry 23 about the pivots 29. When the installation has been placed in the desired position, the chassis 1 and the gantry 23 then being immobilised, the valve 76 is closed, which has the effect of preventing relative rotation of the bearing 28 and of the gantry 23 about the pivots 29.

According to one variant, not shown, of the device in FIG. 7, the chambers of the jacks 68 are in communication with an oil reservoir via pipes each provided with an obturation valve, the above-mentioned pipe 75 being omitted.

This variant has the advantage of compensating in the chambers of the jacks 68 losses of oil which can occur from the obturation valves and also between the pistons 69 and cylinders 70.

In a modified form of embodiment, not shown, of the device in FIG. 7, the two chambers of each jack 68, situated on either side of the piston 69, are connected to one another by a pipe having an obturation valve, the aforementioned pipe 75 being omitted.

In order to ensure an equal variation in volume of the two chambers under the action of the displacement of the piston 69, it is necessary for it to carry a piston rod on each face.

In this modified embodiment, a single jack 68 is sufficient.

In accordance with a non-illustrated variant of this modified embodiment of the device of FIG. 7, the two chambers of each jack 68 are connected to an oil reservoir by ducts each having an obturation valve; the duct connecting the two chambers to one another is omitted.

This variant has the advantage of compensating for any oilleaks which might occur at the valves or between the piston rods 71 and the cylinders 70.

The device for locking the pivots 29 may likewise comprise two discs mounted opposite one another, one on the bearing 28 and the other on the gantry 23. The two discs have a row of perforations into which pins can be inserted in order to hold them fast in relation to one another.

10 To increase the rigidity of the arm 10, the uprights 30 may be extended above this arm 10 and connected thereto by struts 31 and 32.

To improve immobilisation of the jib 8 when the chassis 1 and the carriage or gantry 23 are immobilised, 15 in particular in order to reduce its sensitivity to sidewinds, it may be advantageous to also provide a locking member for the oscillations of the frame 4 on the chassis 1. This locking member may comprise for example obturation valves mounted on the supply circuits of the 20 jacks 57.

If necessary, there may also be provided locking members for the pivot 6 and also possibly for each of the articulations 17 and 25. Each of these locking members may comprise for example two discs or rings mounted opposite one another, respectively on the trunnion and on the bearing of the articulation; the two discs or rings have perforations into which pins can be inserted in order to hold the two discs or rings fast in relation to one another.

The installation illustrated in FIGS. 1 to 9 is intended for the removal towards the continuous conveyor 22 of rocks extracted in the neighbourhood of the chassis 1. For this purpose, the platform 7 has a continuous conveyor 34 and a hopper 35 for supplying this conveyor.

35 This hopper 35 may for example be supplied with rocks by an excavator or another loading machine arranged on the floor 3 of the workings, in the neighbourhood of the chassis 1. The conveyor 34 may consist of a conveyor belt mounted between a drive cylinder 36 and a return cylinder 37 and supported by intermediate rollers 38. The conveyor belt 34 is intended for the conveying of rocks towards a hopper 39 overhanging a continuous conveyor 40 mounted on the arm 9. The conveyor 40 may be a conveyor belt mounted between a drive cylinder 41 and a return cylinder 42 and supported by intermediate rollers 43. The conveyor 40 leads to the end of the arm 9 above a hopper 44 fixed to the arm 9. the hopper 44 discharges into a hopper 77 which axially crosses the trunnion 18 and ends above a continuous conveyor 45 borne by the arm 10 of the jib 8. The hopper 77 may be fixed to the trunnion 18 or to the bearing 20.

50 The continuous conveyor 45 may consist of a conveyor belt mounted between a drive cylinder 46 and a return cylinder 47 and carried by intermediate rollers 48. The continuous conveyor 45 ends at the end of the jib 8 above a hopper 49 fixed to the arm 10. The hopper 49 discharges into a hopper 78 which axially crosses the trunnion 26 and ends above the conveyor 22. The hopper 78 may be fixed to the trunnion 26 or to the bearing 28.

55 Guide plates 50 are provided on the arm 9 either side of the hopper 39 in order to retain on the conveyor 40 the rocks discharged onto it by the conveyor 34 via the hopper 39.

60 Similar plates 51 are provided on the arm 10 in the neighbourhood of the lower end of the hopper 77. The

plates 51 have the function of keeping on the conveyor 45 the rocks which are discharged onto it by the conveyor 40 via the hoppers 44 and 77. A gangway 52 provides access to the platform 7 and gangways 53 provide access from this platform 7 to an upper platform 54 carrying a cab 55 for an operator. The operator's job is to manoeuvre the chassis 1 on the floor 3 of the workings in order to move it towards the areas being worked. The operator also has the job of manoeuvring the gantry 23 on the rails 24 in order to move the end of the jib 8 parallel to the continuous conveyor 22. For this purpose, the gantry 23 is provided with motors, which are not illustrated. During the movement of the chassis 1 on the floor 3 of the workings and/or of the gantry 23 on the rails 24, the stabilisation device constantly and automatically ensures that the axis of rotation of the pivot 6 is vertical by activating the jacks 57 in order to correspondingly swivel the frame 4 on the chassis 1 around universal joints 5.

By means of the combination of the articulations 17 and 25, of the pivot 6 and of the balancing device which constantly holds vertical the axis of this pivot, the axes of rotation of the cylinders 36, 37, 41, 42, 46 and 47 supporting the continuous conveyors 34, 40 and 45 are held constantly horizontal during the movements of the chassis 1 on the ground 3 and/or of the gantry 23 on the rails 24. During these movements of the chassis 1 and/or of the gantry 23 the whole of the jib 8 is articulated freely on the pivot 6 and on the two articulations 17 and 25 (after unlocking of the locking device described above). The jib 8 is thus easily accommodated to these movements. For example, if the chassis 1 is moved closer to the continuous conveyor 22, the two arms 9 and 10 of the jib are folded by one pivoting in relation to the other around the articulation 17 and by pivoting respectively on the pivot 6 on the one hand and on the articulation 25 on the other hand.

On the other hand, if the chassis 1 is moved away from the continuous conveyor 22, the two arms 9 and 10 of the jib 8 are progressively unfolded and, in the event of the chassis 1 being at its maximum distance, the two arms 9 and 10 are brought into alignment with one another.

The arms 9 and 10 carry out corresponding movements if the carriage or gantry 23 is moved on the rails 24, which may be necessary if it is desired to move the chassis 1 a great distance parallel to the rails.

It is thus possible to keep the chassis 1 constantly in the neighbourhood of the zone of the workings being worked while continuing to supply the continuous conveyor 22.

It is preferable to avoid an alignment of the arms 9 and 10, in order to prevent causing the gantry 23 to leave the rails 24. For this purpose there may advantageously be provided a signalling device on the arms 9 and 10, intended to warn the operator when the angle between these two arms is close to 180°. This signalling device may for example comprise a commutator which is mounted on one of the arms 9 and 10 and which is activated by a cam carried by the other arm when the critical angle between the arms is reached, so as to close an electric circuit of an audible and/or visual signal in the cab 55 of the operator.

The installation illustrated in the Figures can easily adapt to a difference of level between the continuous conveyor 22 and the floor 3 of the working zone of the workings, on which the chassis 1 is moved. In fact, in

the case of working of a new deposit, for example when barren rocks covering a workable deposit are being removed, it may happen that the continuous conveyor 22 which removes the barren rocks is established at a level lower than that of this new deposit, for topographical reasons. On the other hand, in the case of a quarry or open-cast mine, it may happen that the floor 3 of the zone of working on which the chassis 1 is being manoeuvred is at a level distinctly lower than that at which the conveyor 22 is set up. By manoeuvring the winch 13 the operator can adjust the inclination of the arm 9 around pivots 11 to suitably distribute the inclination between the arms 9 and 10 of the jib, as a function of the respective levels of the floor 3 and of the rails 24 and of the topography of the site. It may for example be necessary to raise the arm 9 in order to enable the whole jib 8 to pass over an obstacle between the chassis 1 and the gantry 23.

The supply hopper 35 is advantageously provided with a feeder 56 (FIG. 5). For this purpose, the hopper 35 consists of two side elements 58 and 59 each supporting a horizontal cylinder 64 extending the whole length of the hopper.

FIGS. 8 and 9 show in detail the joining of the cylinders 64 to the chassis 1.

The cylinders 64 are rotatably mounted in bearings 80 which are fixed respectively to the two side elements 58 and 59. The element 58 is rigidly connected to a framework 60 firmly connected to the platform 7 of the chassis 1. The element 59 is suspended from the framework 60 by two pairs of connecting rods 81, the connecting rods being articulated respectively on the element 59 around pivots 62 and on the framework 60 around pivots 61. The two elements 58 and 59 are also connected to one another, in the vicinity of the bearings 80, by two pairs of jacks 63, intended to control the distance between the cylinders 64. A roller 103 fixed to the central part of the element 59 is retained laterally in a guide 104 firmly connected to the chassis 60 during movement of the element 59 in relation to the element 58. The roller 103 and the guide 104 have the function of preventing a lateral displacement of the element 59. The assembly of the connecting rods 81, of their articulations 61 and 62, of the roller 103 and of its guide 104 permits if necessary an asymmetrical separation of the two cylinders 64 in the event that the pressure in one of the jacks 63 passes a predetermined value. By controlling the speed of rotation of the cylinders 64 and their separation by means of the jacks 63 it is possible to control as desired the rate at which material falls on to the conveyor 34. The cylinders 64 may be provided at their periphery with toothed transverse covering plates 65 enabling the crushing and breaking-up of the material. A cleaning device (not illustrated) is provided to clean the gaps between the teeth 65, whatever be the speed of the cylinders 64.

When the continuous conveyor 22 consists of a conveyor belt, it is advantageous to provide the gantry 23 with several successive parallel rows of rollers 66. The rows of rollers 66, arranged transverse to the conveyor belt 22 and usually called "support garlands", are intended to support temporarily the belt 22 in order to raise it in the vicinity of the outlet orifice of the hopper 78. There is thus greatly reduced the impact of the rocks falling on to the belt 22, which prevents damage to or early wear of the belt 22, in particular in the case of abrasive rocks.

The installation is provided with a motor coupled to pumps for a hydraulic fluid. The pumps are intended for supplying the jacks 57 and 63 and also hydraulic motors for driving the caterpillars 2, the conveyors 34, 40 and 45, the gantry 23 and the cylinders 64 of the feeder 56. The control of the motors and of the jacks 63 and of the devices and locking members described above is effected by the operator from the cab 55. The jacks 57 are controlled automatically by the stabilisation device.

In the event that the present exploitation zone of the deposit is of wide area, it is advantageous to mount the continuous transporter 22 and the rails 24 on a structure which is transversely displaceable over the ground, for example by sliding. In this way there is considerably increased the space available for movement of the chassis 1 on the floor 3 of the workings, at the same time increasing the possibilities of use of the machine in accordance with the invention.

In FIG. 10 there is represented a variant of the chassis of the installation of FIGS. 1 to 9.

The platform 7 of the chassis in FIG. 10 carries a structure 82 on which there is articulated an auxiliary jib 83 around horizontal pivots 84. The auxiliary jib 83 is suspended by means of a tackle 85 from another jib 86 forming part of the structure 82.

The platform 7 has another vertical pivot 87 whose vertical axis of pivot is substantially in the production of the vertical axis of the pivot 6. The pivot 87 consists of a bearing fixed to the platform 7 and of a trunnion rotatably mounted in this bearing. The trunnion carries the horizontal articulation pivots 11 of the arm 9 of the jib 8. The arm 9 can thus pivot at the same time around a horizontal axis on its pivot 11 and around a vertical axis on its pivot 87.

On its upper part the structure 82 carries another vertical pivot 111 whose vertical axis of rotation is essentially in the production of the common vertical axis of the pivots 6 and 87. The vertical pivot 111 carries another auxiliary jib 112 from which there is suspended the arm 9 and the articulation 17 by means of a tackle 113.

The respective pivotings of the arm 9 and of jib 112 in relation to the structure 82 and the platform 7 around their vertical pivots 87 and 111 are synchronized.

The auxiliary jib 83 carries at its free end a scoop wheel 114. This is designed in per se known way to extract rocks from the deposit and to deliver them to a continuous conveyor 115 provided on the jib 83. The continuous conveyor 115 ends above a hopper 116 discharging into the hopper feeding the continuous conveyor 40 of the jib 8.

In the above description of FIGS. 1 to 10 the articulation 17 is suspended from an upright 16 carried by the chassis 1. It is evident that by way of variation the articulation 17 may be suspended from a structure carried by the carriage 23, for example by means of a cable connecting the structure to the arm 10 of the jib 80.

FIGS. 11a, 11b and 12 show a modified embodiment of the installation of FIGS. 1 to 9.

The installation of FIGS. 11 and 12 likewise comprises a chassis 1 moveable on the floor of the workings, a carriage 23 moveable on a rolling track 24 along the continuous conveyor 22 and an articulated jib 8 connecting this chassis 1 to the carriage or gantry 23. The assembly consisting of the chassis 1, the jib 8 and

the carriage 23 may be in a similar form to the installation of FIGS. 1 to 9, in particular as regards the articulations of the two arms 9 and 10 of the jib 8 on one another and on the chassis 1 and on the carriage 23.

5 The installation or arrangement in FIGS. 11 and 12 further comprises an additional vehicle 88.

The vehicle 88 is constructed in a similar way to the frame 1 of the arrangement in FIGS. 1 to 9. It will not be described in detail in this specification, it being understood

10 that the elements of the vehicle 88 which are located on the chassis 1 will carry the same reference numbers together with a "prime" sign. In particular the vehicle 88 is provided with a frame which can be swivelled in sight, similar to the frame 4 of the chassis 1, on which is mounted rotatably a platform 7'. The connection of the orientable frame to the vehicle is so designed as to ensure constantly the verticality of the axis of rotation of the platform 7'.

15 The arrangement in FIGS. 11 and 12 further comprises a second jib 89, connecting the vehicle 88 to the chassis 1.

20 The second jib 89 is similar in design to the jib 8 of the arrangement in FIGS. 1 to 8. It will not be described in more detail in this specification, it being understood that the elements of the jib 89 which are located on the jib 8 will carry the same reference numbers together with a prime sign. In particular the jib 89 consists of two articulated arms 9' and 10'. The arm 9' is articulated to the platform 7' of the vehicle 88 on pivots 11' round an axis transverse to the arm 9'.

25 The arm 10' is connected at one of its ends to the arm 9' by an articulation 17' which is similar to the articulation 17 represented in detail in FIG. 3 and described above.

30 The articulation 17' and the end of the arm 10' which is articulated to it are suspended from a structure 16' of the vehicle 88 by means of a cable 12' fixed to the arm 9', in a similar way to that in which the articulation 17 is suspended from the structure or upright 16 supported by the chassis 1.

35 The arm 9' carries a conveyor 40' which extends below the downstream end of the conveyor 34' of the vehicle 88, to above a conveyor 45' carried by the arm 10'.

40 The arm 10' of the jib 89 is further articulated to the chassis 1 via an articulation 90. The articulation 90 comprises a trunnion 91 rotatably mounted in a bearing 92. The bearing 92 is fixed to a superstructure 93 of the platform 7 of the chassis 1, in such a way that the axis of rotation of the trunnion 91 in the bearing 92 lies in the extension of the axis of rotation of the pivot 6. The trunnion 91 is further articulated to two uprights 94 of the arm 10' of the jib 89, on two pivots 95 round an axis substantially transverse to the arm 10' and perpendicular to the axis of rotation of the trunnion 91 in the bearing 92.

45 In the articulation 90 the trunnion 91 and the bearing 92 may be two cages of a ball or roller bearing.

50 The trunnion 91 is traversed by a hopper 96 which overhangs in continuous conveyor 34 of the platform 7.

55 A hopper 97 fixed to the end of the arm 10' opens into the hopper 96 and is designed for the transfer of rocks or stones from the conveyor 45' of the jib 89 on the conveyor 34 of the chassis 1 via the hopper 96.

A counterweight 102 is suspended from the arm 10' beyond the articulation 90, to balance the jib 89 and its articulation 17'.

In the arrangement represented in FIGS. 11 and 12 the jib 89 and the platform 7 pivot round a common vertical axis during the displacement of the vehicle 88 and/or of the chassis 1 and/or of the carriage 23.

In a variant, which is not shown, of the arrangement of FIGS. 11 and 12, the common axis of the pivots 11 of articulation of the arm 9 to the platform 7, is located in a vertical plane passing through the common vertical axis of the articulations 6 and 90. In this variant arrangement the ends of the arms 9 and 10' articulated to the frame 1 are constantly vertically in line one with the other, so that the conveyor 34 can be omitted.

FIG. 13 represents another variant of the chassis 1 of the arrangement of FIGS. 11 and 12.

The chassis represented in FIG. 13 differs from the chassis 1 in FIG. 12 in that the vertical rotation axis of the articulation 90 is not in the extension of the vertical rotation axis of the articulation 6.

FIG. 14 represents diagrammatically another particular form of embodiment of the arrangement of FIGS. 1 to 9.

The arrangement represented in FIG. 14 is designed similarly to the arrangement described above of FIGS. 1 to 9. It further comprises an additional vehicle 98 which can move over the ground of the workings and a second jib 99 consisting of two articulated arms 100 and 101 connecting the vehicle 98 to the carriage 23.

The vehicle 98, the jib 99 and the connection of the jib 99 to the vehicle 98 and to the carriage 23 are designed similarly to the arrangement in FIGS. 1 to 9. In particular the arm 101 of the jib 99 is connected to the carriage 23 by an articulation 25' similar to the articulation 25, the articulation 25' being connected to the carriage 23, beside the articulation 25, in such a way as to overhang the continuous conveyor 22.

The arrangement in FIG. 14 may be considered as consisting of two of the installations in FIGS. 1 to 9, paired. It is adapted to transfer towards the single continuous conveyor 22 stones or rocks extracted simultaneously from two separate seam or deposit zones. The two seam zones may possibly be at different levels.

What we claim is:

1. An installation for the evacuation of material comprising rocks or stones from a work site, comprising:
  - a hopper (35) for receiving said material,
  - an upper framework (60) supporting said hopper (35),
  - an intermediate framework (4) carrying the upper framework (60),
  - an articulated connection (6) by which the upper framework (60) is mounted on the intermediate framework (4) for rotation about a substantially vertical axis,
  - a lower framework (1) mounted on crawler treads (2) for moving over the ground and supporting the intermediate framework (4),
  - stabilization means (5, 57) for maintaining the intermediate framework (4) substantially horizontal on the lower framework (1),
  - a first endless conveyor (34) carried by the upper framework (60) and receiving material from said hopper (35),

a second endless conveyor (40) receiving material from the first conveyor (34) and in substantial alignment with the first conveyor (34),

a first arm (9) carried by the upper framework (60) and carrying the second conveyor (40),

articulation means (11) by which the first arm (9) is supported on the upper framework (60) for vertical swinging movement about a substantially horizontal axis,

a third endless conveyor (45) receiving material from the second conveyor (40),

a second arm (10) suspended from the first arm (9) and carrying the third conveyor (45),

articulation means (17, 20, 21) between the first (9) and second (10) arms for mounting the second arm (10) for vertical and horizontal swinging movement relative to said first arm (9),

a second hopper (44, 51) in at least two portions of which the upper portion (44) is carried by the first arm (9) and receives material from the second conveyor (40) and of which the lower portion (51) is carried by the second arm (10) and receives material from the upper portion (44) to feed material to the third conveyor (45),

a discharge conveyor (22) for said material, a mobile gantry (23) movable along the discharge conveyor (22) and supporting the second arm (10) at the end of the second arm opposite the first arm (9).

articulation means (27-29) between the second arm (10) and the gantry (23) for movement of the second arm relative to the gantry about horizontal and vertical axes,

at least one counterweight (33) carried by the second arm (10) to balance the second arm about the articulation means (27-29),

and a discharge hopper (49, 78) in at least two superposed portions of which the upper portion (49) is carried by the second arm (10) and receives material from the third conveyor (45) and of which the lower portion (78) is carried by the gantry (23) and receives material from the upper portion (49) for transmitting the material to the discharge conveyor (22).

2. An installation as claimed in claim 1, in which said articulated connection (6) of the upper framework (60) to the intermediate framework (4) comprises a trunnion having upper and lower races the upper of which is fixed to the upper framework (60) and the lower of which is fixed to the intermediate framework (4).

3. An installation as claimed in claim 1, in which said stabilization means (5, 57) comprises a universal joint (5) and jacks (57) carried by the lower framework (1) and acting on the intermediate framework (4).

4. An installation as claimed in claim 1, in which the articulation means (17, 20, 21) of the second arm (10) to the first arm (9) comprises a trunnion (17, 18, 20) disposed about a vertical axis and having an upper race (18) fixed to the first arm (9) by means of substantially horizontal pivots (19) and having a lower race (20) connected to the second arm (10) by means of substantially horizontal pivots (21), the axes of said pivots (19 and 21) being coplanar.

5. An installation as claimed in claim 1, in which the articulation means (25-29) of the second arm (10) on the gantry (23) comprises a trunnion (25, 26, 28) dis-

15

posed on a substantially vertical axis and having an upper race (26) which supports the second arm (10) by means of substantially horizontal pivots (27) and having a lower race (28) carried by said gantry (23) by means of substantially horizontal pivots (29) the axes 5 of said pivots being coplanar, and jacks (68) acting between the gantry (23) and said lower race (28) thereby to maintain the axis of the trunnion substantially vertical.

6. An installation for the evacuation of material comprising rocks or stones from a work site, comprising: 10 a hopper (35) for receiving said material, vehicle means (1, 2, 4, 60) mounting said hopper for movement over the ground, first endless conveyor means (34 and 40) mounted 15 on the vehicle means for receiving material from the hopper (35), second endless conveyor means (45) receiving material from the first conveyor means (34 and 40), means interconnecting the first and second conveyor means at least for relative horizontal swinging movement about a vertical axis,

16

a discharge conveyor (22) for the material, a gantry (23) movable along the discharge conveyor (22) and supporting an end of the second conveyor means (45) remote from the first conveyor means (34 and 40), a trunnion (26, 28) having two portions (26 and 28) rotatable relative to each other about a substantially vertical axis, means (27) interconnecting one (26) of said trunnion portions with said second conveyor means (45) for relative vertical swinging movement about a first substantially horizontal axis transverse to said second conveyor means (45), and means (29) interconnecting the other (28) of said trunnion portions with said gantry (23) for relative vertical swinging movement about a second horizontal axis transverse to said discharge conveyor (22). 7. An installation as claimed in claim 6, in which said first and second horizontal axes are substantially coplanar.
